Primary Examiner — Sheryl Lane*Assistant Examiner* — Lilyana Bekic(74) *Attorney, Agent, or Firm* — Goodwin Procter LLP(57) **CLAIM**

The ornamental design for an indicator for an inhaler, as shown and described.

DESCRIPTION

FIG. 1 is a front perspective view of an indicator for an inhaler in a position of use;

FIG. 2 is an enlarged front view of the indicator for an inhaler;

FIG. 3 is an enlarged rear view of the indicator for an inhaler;

FIG. 4 is an enlarged right side view of the indicator for an inhaler;

FIG. 5 is an enlarged left side view of the indicator for an inhaler; and,

FIG. 6 is an enlarged top view of the indicator for an inhaler. The broken line showing of the inhaler in FIG. 1 illustrates the environment of the claimed design and forms no part thereof.

1 Claim, 3 Drawing Sheets# US D752,204 S
